UNITED STATES PATENT OFFICE.

AUGUST WILHELM HEINRICH WOIZESKI, OF BLOOMINGTON, ILLINOIS.

DESIGN FOR A RAKE.

SPECIFICATION forming part of Design No. 26,659, dated February 16, 1897.

Application filed December 29, 1896. Serial No. 617,409. Term of patent 14 years.

To all whom it may concern:

Be it known that I, AUGUST WILHELM HEINRICH WOIZESKI, a citizen of the United States, residing at Bloomington, in the county of McLean and State of Illinois, have invented and produced a certain new and original Design for Rakes; and I do declare the following to be a full, clear, and exact description of the invention, such as will enable others skilled in the art to which it appertains to make and use the same.

My invention has relation to a design for a garden-rake. It relates to the entire configuration of the rake.

My invention relates particularly to a rake, as illustrated in the accompanying drawings, in which—

Figure 1 is a perspective view of a rake embodying my design, and Fig. 2 is a transverse section through the line $x x$.

The leading features of my design appear in the following description.

1 represents the cylindrical handle; 2, the

cylindrical shank, which extends centrally from the cylindrical cross-rod 3, arranged at 25 a right angle to said shank, and 4 4 represent a series of sockets mounted on said cross-rod 3. Each socket is provided with a blade 5, curved at its outer end and terminating in a diamond-pointed shovel-tooth 6. The under 30 longitudinal edge of the blades terminates in a knife-edge, as shown in Fig. 2, and the whole series is arranged in parallel lines and at a right angle to the cross-rod 3.

Having thus fully described my design, 35 what I claim as new, and desire to secure by Letters Patent of the United States, is—

The design for a garden-rake, substantially as herein shown and described.

In testimony whereof I hereunto affix my 40 signature in presence of two witnesses.

AUGUST WILHELM HEINRICH WOIZESKI.

Witnesses:

A. M. MILLER,
L. B. CARLOCK.
